Primary Examiner—Lucy Lieberman*(74) Attorney, Agent, or Firm*—Pendorf & Cutliff**(57) CLAIM**

The ornamental design for a combined metal bottle and cap, as shown and described.

DESCRIPTION

FIG. 1 is a front view of a combined metal bottle and cap showing my new design, the rear view being the same; FIG. 2 is a top plan view thereof; and, FIG. 3 is a bottom plan view thereof.

The portions of the base of the combined metal bottle and cap that are not shown in the drawings or described in the specification do not form part of the claimed design.
